UNITED STATES PATENT OFFICE.

HARTLEY O. BAKER, OF PUEBLO, COLORADO, ASSIGNOR TO THE BAKER STEAM MOTOR CAR AND MANUFACTURING CO., INC., OF PUEBLO, COLORADO.

HYDROCARBON-BURNER.

1,369,074.

Specification of Letters Patent. Patented Feb. 22, 1921.

Application filed June 3, 1919. Serial No. 301,413.

To all whom it may concern:

Be it known that I, HARTLEY O. BAKER, a citizen of the United States, residing at Pueblo, in the county of Pueblo and State 5 of Colorado, have invented certain new and useful Improvements in Hydrocarbon-Burners; and I do hereby declare the following to be a full, clear, and exact description of the invention, such as will enable others 10 skilled in the art to which it appertains to make and use the same.

The present invention relates to hydrocarbon burners, and is particularly an improvement over the hydrocarbon burner 15 disclosed in my copending application filed February 26, 1918, Serial No. 219,284.

The primary object of this invention is the provision in a hydrocarbon burner, adapted especially for use under the steam 20 generator or water boiler of a steam motor vehicle, of novel means for the admission of a large quantity of air to mix with the gas, whereby to increase the efficiency of combustion and to provide maximum heat and 25 other benefits.

By way of explanation it may be stated that experience has shown that the ordinary Bunsen burner including a jet nozzle and a mixing tube, is not efficient when used under certain conditions, such as within an inclosed boiler or the like, in which arrangement the structure is not capable of producing a sufficient inflow of air to insure 30 complete combustion of the fuel, this being especially true when the burner is placed under a boiler and is inclosed. The incasing of the burner results in a resistance to the draft, thereby checking or retarding the flow of air and gas and choking, more or less, 35 the combustion of fuel, because sufficient flow of air is not established. Tests have shown that the use of such a burner under a boiler, with the casing opened for free circulation of air from the atmosphere, resulted in the mixture burning with a blue 40 flame thirty inches high, whereas the same burner under the same conditions, excepting with the boiler incased, will choke the flame

down to a height of three inches or less. Such tests have exemplified the need for a greater flow of oxygen, as well as indicating that the flames draw oxygen from the surrounding air, which is not possible with the incasing of the burner. Thus, the gas in being shot through the mixing tube does not draw in sufficient air to support complete combustion, resulting not only in incomplete combustion of the fuel, but also in a loss of heat units, the unburned fuel passing into the smoke stack and out into the air. This results in a fire of reduced heat, when it should be of higher temperature.

The invention therefore has for its object to so construct and arrange the air inlet means with respect to the fuel nozzle or nozzles, as to obtain a maximum supply of air to admix with the fuel and provide a thoroughly combustible mixture which will support a blue flame of maximum height and heat.

A further object is the provision of a mixing tube of novel form, with one or more air funnels or bells between the fuel nozzle and mixing tube, whereby the fuel in shooting through the funnel or funnels and mixing tube will draw in a large quantity of air, sufficient for the needs.

A still further object is the provision in combination with a main fire burner, of a primary or pilot burner assembled therewith in a novel manner, to start the generation of vapor for the main burner whenever required.

The invention has for a further object the combination with the main and pilot burners, of a vaporizing device between the generating piping and the main burner or burners, whereby to enhance the vaporization of the fuel passing to the main burner, and to also arrest particles of foreign matter, as well as providing other advantages.

With the foregoing and other objects in view, which will be apparent as the description proceeds, the invention resides in the construction and arrangement of parts hereinafter described and claimed, it being

understood that changes can be made within the scope of what is claimed without departing from the spirit of the invention.

The invention is illustrated in the accompanying drawings, wherein—

Figure 1 is a plan view of the improved burner, portions being broken away.

Fig. 2 is a horizontal section in the plane of the mixing tubes.

10 Fig. 3 is an enlarged fragmentary front view of the burner.

Fig. 4 is an enlarged vertical section taken on the line 4—4 of Fig. 1.

15 Fig. 5 is a view similar to Fig. 2 showing a modification.

Fig. 6 is a vertical section taken on the line 6—6 of Fig. 5.

The construction, in general respects, is somewhat similar to the burner disclosed in 20 the above mentioned application, and is intended primarily for use under a water boiler or steam generator, such as used in steam motor vehicles, although the use of the present improvements is not limited to 25 such particular use of the burner. The main burner, which is of duplicate or twin construction, includes a casing 1 inclosing two gas distributing chambers 2 disposed side by side and separated by a partition 3 extending from the front to the rear in a vertical plane, the front wall 4 of the casing being preferably straight with the partition 3 extending to said wall between the ends thereof. The top 5 of the casing 1 has the 30 gas outlet slits 6 arranged in rows, and said top has channels or grooves 7 extending forwardly and rearwardly between the rows of slits or outlets to accommodate the generating piping 8 which extends back and forth in said channels or grooves. The piping 8 35 preferably comprises two branches or pipes leading from a common supply pipe 9 for gasolene, kerosene or other suitable liquid fuel.

40 The casing 1 is provided in front of the wall or partition 4 and the respective gas chambers 2, with the air chambers 10 having the front wall 11, and the casing is provided in front of the wall 11 with a chamber or space 12 for controlling valves, closed by a removable door or panel 13. The casing is further provided between the chambers 10 and at the forward end of the partition 3 with a recess or pocket 14 opening upwardly 45 and also opening forwardly through the partition 11, and the pilot or primary burner 15 is inserted and seated in said recess 14.

50 The pilot or primary burner 15 comprises a casing 16 to fit snugly in the recess 14, and said casing has a longitudinal partition 17 extending from the forward to the rear end of the casing between the top and bottom thereof, and dividing the interior of the

65 casing into the upper gas distributing chamber 18 and the lower air inlet chamber or passage 19. The bottom of the casing 16 is provided near the rear end thereof with an inlet opening or port 20 which registers with an air inlet opening or port 21 in the 70 bottom of the casing 1, thus admitting fresh air into the rear end of the passage 19, so that said air flows forwardly under the partition 17, thus receiving its initial heat from the partition 17 and walls of the casing 16 75 which are heated from the flames. The top of the casing 16 has the gas outlets 22, and the forward end portion of the partition 17 is offset upwardly, as at 23, and carries the mixing tube 24 which extends rearwardly from said outlet portion over the partition 17 into the chamber 18. A fuel nozzle 25 extends rearwardly through the forward end of the casing 16 to shoot the vapor or fuel through the mixing tube 24, 80 whereby air is drawn into and forwardly within the passage or chamber 19 and thence upwardly within the forward upwardly extending portion thereof to mix with the fuel and flow through the tube 24. A generator 85 pipe 26 is connected to the nozzle 25 and extends around the upper outlet portion of the casing 16 and is connected to the supply pipe 27 for the fuel used for the pilot burner. The pilot burner thus receives its fresh air 90 from underneath.

95 The main fuel nozzles 28 extend rearwardly through the wall 11 into the air chambers 10, and in alignment with the mixing tubes 29 carried by the wall or partition 4 and extending rearwardly into the chambers 2. These tubes 29 have their forward ends flared abruptly and projecting within the chambers 10, and the rear ends of said tubes flare or enlarge more gradually, as 100 clearly seen in Fig. 2. Between each mixing tube 29 and the corresponding fuel nozzle 28 is an air funnel or bell 30, having its forward larger end surrounding the nozzle, and its rear small end located within the forward flared end of the mixing tube. This funnel 30 tapers rearwardly to extend within the forward portion of the mixing tube 29 which also tapers rearwardly to the restricted portion of the mixing tube, from 105 which point the mixing tube increases in diameter or flares. The funnel 30 is supported from the mixing tube 29 by means of wires 31 or the like. The fuel thus flows from the nozzle 29 through the funnel 30 110 and thence through the mixing tube 29, providing a double inflow of air, because the air will be drawn into the funnel 30 with the fuel, and the stream of fuel and air in passing from the rear contracted end of the 115 funnel 30 through the mixing tube 29 will draw a further supply of air into the mixing tube between the funnel and forward

flared end of the mixing tube. This results in a copious supply of air being drawn into the corresponding chamber 2 with the fuel, and the gas or mixture can circulate within 5 said chamber, so as to be distributed to flow through all of the upper outlets 6 with equal pressure and density.

By thus delivering more than ample air with the fuel into the distributing chambers 2, complete combustion of the fuel is obtained, and at the same time, a greater pressure of the gas is maintained, thereby forcing the products of combustion up through the boiler and increasing the draft. The result is twofold, in that more air is drawn into the burner to support combustion, and the draft is "forced," which is especially desirable with a down draft wherein the smoke stack extends downwardly from the boiler, 20 as in a steam automobile. This feature, which is essential in automobile practice, has been a great draw-back, and is overcome by the present arrangement. The combustion of the fuel being made thorough by the abundant supply of air, will naturally produce greater heat and increase the volume 25 of steam produced, whereby a greater quantity of steam can be supplied, or the boiler constructed on a smaller scale to supply the same volume of steam as with the ordinary boiler having the usual air supply.

The air chambers 10 have the entrance portions or mouths 32 extending from the opposite portions of the chambers 10 and 35 extending or curving rearwardly partially around the side walls of the casing 1, and suitable air controlling shutters 33 are provided in the mouths of the entrance portions 32, whereby the flow of air into the chambers 10 can be controlled, should the maximum volume of air not be required or desired. The shutters can thus be used to regulate the volume of air, which may vary 40 according to different temperatures, or under different barometric conditions at different altitudes.

The area of the air funnel 30 at its rear contracted end is less than the area of the throat of the mixing tube 29, whereby the 50 stream of vapor and air passing from the funnel into the mixing tube will pass through the mixing tube with minimum resistance, and the flaring of the forward receiving end of the mixing tube will permit 55 the air to rush in with little resistance. The flaring of the funnel 30 also permits a large amount of air to pass into the funnel with the fuel. Thus, the mouths and throats of both the funnel and mixing tube 60 are of increased diameters or areas from the funnel to the mixing tube, providing for a high velocity of the fuel and air in entering and passing through the funnel and mixing tube, without creating back-pres-

sure. Even though excess air is drawn into 65 the burner, this is not objectionable, because the heat is not reduced, and is even increased by the blow torch effect. The arrangement also eliminates the necessity of using a steam jet for increasing the flow of air and pressure, since these results are obtained as above set forth. The present arrangement also muffles the noise that is usually attendant to a burner using a large quantity of 70 air.

A vaporizing device is used between the generating piping 8 and the fuel nozzles 28 and is so arranged and constructed that the liquid fuel is vaporized more thoroughly and completely before it reaches the nozzles, 75 that the vaporization is established much quicker and without the smoking of the burner as usual, that any imperfectly vaporized fuel or particles thereof will be trapped in the vaporizing chamber and properly 80 converted into vapor before passing to the nozzles, and that any particles of carbon deposit, chips of metal or other foreign matter passing from the generating piping toward the nozzles will be caught and arrested in the vaporizing chamber to prevent 85 clogging of the nozzles. This device includes an elongated chamber 34 disposed in a horizontal longitudinal position over the pilot burner 15 so as to be heated thereby, the chamber 34 being disposed above the outlets 22 so that the flames of the pilot burner rise against the bottom of and along the sides of the chamber 34. These discharge terminals of the piping 8 extend forwardly along the opposite sides of the chamber 34 longitudinally thereof, and are connected to T-couplings 35 which have removable clean out plugs 36, and said couplings are connected to opposite sides of the chamber 34 near the forward end and bottom 90 thereof, providing inlets 37 for such chamber, whereby the vapor enters the chamber near the bottom and the forward end thereof, to pass rearwardly and upwardly there- 95 in. The forward end of the chamber 34 has a removable clean out plug 38 near the bottom, which can be removed for cleaning out sediment and accumulations from within the chamber. The vapor is discharged from 100 the chamber 34 through a longitudinal pipe 39 which extends through the forward end of the chamber near the top thereof and along the top of the chamber to a point near the rear end of the chamber, so that 105 the vapor in flowing through the ports 37 into the chamber must pass rearwardly within the chamber and thence upwardly into the pipe 39 in which the vapor flows forwardly into the X-coupling 40 connected 110 to the forward end of the pipe 39. This coupling 40 has a removable clean out plug 41 to clean out the pipe 39, and branches 115

42 are connected to the coupling 41 and diverge downwardly to supply the vapor to the nozzles 28. The branches 42 are connected to couplings 43 from which the nozzles 28 extend rearwardly, and said couplings are provided thereon with removable rolls or cylinders 44 of wire mesh, to provide screens to arrest any particles which might possibly pass through the chamber 34 and pipe 39. The couplings 44 have lower removable clean-out plugs 45 on which any sediment or foreign particles will rest, so that they can be cleaned out by removing said plugs from time to time. In 10 cleaning out the chamber 34, the plugs 41 and 38 can be removed, and steam or air forced inwardly through the pipe 39 to blow out any accumulations through the opening left by the removal of the plug 38.

20 The delivery portions of the piping 8 being located at opposite sides of the chamber 34 above the pilot burner 15 will be heated, as well as the chamber 34, and when the main burner is turned on and lighted, the 25 liquid in passing from the pipes 8 into the chamber 34 is vaporized thoroughly and complete before it passes the nozzles. Thus, even though the vaporization in the piping 8 is not complete, the vapor in passing into the chamber 34 will be permitted 30 to expand and dry out, and the dry vapor will pass rearwardly and upwardly into the pipe 39 in a thoroughly vaporized condition and thence to the nozzles 28. Should imperfectly vaporized fuel or particles pass 35 into the vaporizing chamber 34, the same will remain at the bottom thereof, while the gas or vapor will pass upwardly into the pipe 39, and this will prevent the main 40 burner from being flooded with raw fuel, avoiding the flow of liquid fuel to and through the nozzles. This chamber 34 provides for a quicker vaporization of the liquid, and instead of causing the burner to 45 smoke with a white smoke, as most burners usually do when first started after they have cooled this burner commences to burn immediately with a blue flame. The main burner when lighted heats up the generating 50 piping 8 throughout its length, thus completing the vaporization in the piping 8. Another advantage in the use of the present construction is the function of the chamber 34 as a trap for catching and arresting 55 foreign matter that may flow with the vapor toward the nozzles. Frequently, carbon deposits form in the generating piping, and this deposit suddenly lets go and is carried along with the vapor to the nozzles, clogging 60 them, and requiring cleaning out of the nozzles. In the present construction, such particles of carbon deposit will pass into the chamber 34 and drop the bottom thereof, where they will remain until the

chamber is cleaned out. It has also been 65 found that in bending the piping 8, small particles of metal chip off from the interior due to the bending of the pipe, and even though the pipes are cleaned out, frequently 70 some pieces of metal remain therein and will be carried later on with the vapor to the nozzles. Such chips or pieces of metal will be caught in the chamber 34, however, so 75 that they will not possibly clog the nozzles. The chamber 34 will also equalize the pressure 80 from the two branches of the piping 8, which both discharge into the one chamber, from which the gas will flow with uniform pressure to the nozzles, even though the pressure in one branch or the other of the 85 piping 8 is greater. The retarded flow of vapor in one branch of the generator piping will therefore not result in unequal pressures at the two nozzles 28, thereby 90 providing for uniform heat throughout the 95 area of the main burner, and avoiding unequal heating at the opposite sides as well as whistling which results from abnormal or unequal pressures.

In the modified form shown in Figs. 5 90 and 6, two air funnels 30 are provided between each mixing tube 29 and nozzle 28, being of increased sizes from the nozzle to the mixing tube. It will be noted that the throats and mouths of the funnels and mixing tube gradually increase in diameter or area from the nozzle rearward. This provides for an additional inflow of air through the second air funnel and by increasing the sizes of the throats of the funnels and mixing tube, the abundant inflow of air is provided without back-pressure or objectionable resistance. Any number of air funnels can be used, it being noted that the forward or receiving end of the mixing tube 100 29 is also flared or funneled, while the rear end thereof is enlarged or flared to permit the gas or mixture to expand as it leaves the mixing tube, thus enabling the mixture to maintain its high velocity and to assure 105 of high pressure of the gas in the chamber 2.

Figs. 5 and 6 also illustrate another change from the construction above described, in that the entrance portions 32 of the chambers 10 are tubular and extend 110 away from one another at the opposite portions of the chambers 10 and then extend upwardly at the exterior of the boiler, being provided with shutters 33 in the mouths 115 thereof to regulate the entrance of air.

Having thus described the invention, what is claimed as new is:—

1. A hydrocarbon burner embodying a gas distributing chamber, an air chamber, a partition between said chambers, a mixing 125 tube carried by said partition and extending into the gas distributing chamber, said tube having a flared mouth extending within the

- air chamber, a fuel nozzle projecting within the air chamber to direct fuel through said air chamber into the mixing tube, an air funnel of flared form between said nozzle and mixing tube having its larger end arranged toward said nozzle and its smaller end arranged toward the mouth of the mixing tube, said air chamber having an entrance portion extending therefrom, and a shutter within said entrance portion to control the inflow of air.
2. A hydrocarbon burner embodying a casing having a main burner, a recess and an air inlet opening at the bottom of said recess, and a pilot burner fitted in said recess and having a lower air inlet opening to register with the aforesaid opening.
3. A hydrocarbon burner embodying a casing having a pair of air chambers, a recess between said chambers, and an air inlet opening at the bottom of said recess, mixing tubes extending from said chambers, fuel nozzles for directing fuel from the air chambers through said tubes, and a pilot burner including a casing fitting in said recess and provided with a lower air inlet opening to register with the aforesaid opening.
4. A hydrocarbon burner including a casing having a longitudinal partition providing a gas distributing chamber at one side thereof and an air inlet passage at the opposite side, the casing having an air inlet opening at one end of said passage, the partition having an offset portion at the other end of said passage, a mixing tube carried by said offset portion and projecting into the gas distributing chamber, and a fuel nozzle projecting toward said offset portion to deliver fuel through said mixing tube.
5. The combination of a main burner, a nozzle for delivering fuel thereto, a pilot burner, a vapor chamber arranged to be heated by the pilot burner, generating piping arranged to be heated by the main burner and having its delivery portion adjacent to said chamber to be heated by the pilot burner, said delivery portion of the generating piping being connected to one portion of said chamber, and means for conducting vapor from the opposite and upper portion of said chamber to the fuel nozzle.
6. The combination of a main burner, a pilot burner, a fuel nozzle for delivering fuel to the main burner, a vapor chamber arranged to be heated by the pilot burner, generating piping arranged to be heated by
- the main burner and having its delivery portion adjacent to said chamber to be heated by the pilot burner and connected to said chamber near one end thereof, and a vapor outlet pipe extending through said end of the chamber to a point near the opposite end and having its outer end connected to said nozzle.
7. The combination of a main hydrocarbon burner, a pilot hydrocarbon burner, a generator pipe having its discharge terminal disposed above the pilot burner to be heated thereby, the remaining portion of said pipe being disposed over the main burner, a vapor chamber disposed over the pilot burner and connected to the discharge terminal of the generator pipe to receive the vapor therefrom and to catch foreign matter, and means for conducting the vapor from said chamber to the main burner.
8. The combination of a main burner, a pilot burner, a plurality of generator pipes having their main portions located above the main burner and their discharge terminals located above the pilot burner, a vapor chamber located above the pilot burner, the discharge terminals of said pipes communicating with said chamber to deliver the vapor into said chamber and equalize the pressure therein, and a plurality of vapor nozzles for the main burner communicating with said chamber to receive vapor therefrom.
9. The combination of a main burner, a pilot burner, a plurality of generator pipes having their main portions located above the main burner and their discharge terminals located above the pilot burner, an elongated horizontal vapor chamber located above the pilot burner, the discharge terminals of said pipes being located longitudinally along said chamber and communicating with one end portion of said chamber to discharge vapor and foreign matter into said chamber, a plurality of vapor nozzles for the main burner, and a connection between the nozzles and chamber communicating with the other end portion of said chamber to receive vapor therefrom.

In testimony whereof I have signed my name to this specification in the presence of two subscribing witnesses.
